UNITED STATES PATENT OFFICE.

STEFAN MICUCH, OF HYDE PARK, PENNSYLVANIA.

DESIGN FOR A PICTURE-FRAME.

46,601.

Specification for Design.

Patented Oct. 27, 1914.

Application filed July 27, 1914. Serial No. 853,545. Term of patent 7 years.

To all whom it may concern:

Be it known that I, STEFAN MICUCH, a subject of the King of Hungary, residing at Hyde Park, in the county of Westmoreland and State of Pennsylvania, have invented a new, original, and ornamental Design for Picture-Frames, of which the following is a specification, reference being had to the accompanying drawing, forming part thereof.

The figure is a plan view of a picture frame, showing my new design.

I claim:

The ornamental design for picture frames, as shown.

STEFAN MICUCH.

Witnesses:

MARTIN ZULBAZ,
STIF PASTVA.
